United States Patent Office.

F. M. REYNOLDS, OF MILE STRIP, NEW YORK.

Letters Patent No. 80,222, dated July 21, 1868.

IMPROVEMENT IN HAY-LOADERS.

The Schedule referred to in these Letters Patent and making part of the same.

TO ALL WHOM IT MAY CONCERN:

Be it known that I, F. M. REYNOLDS, of Mile Strip, in the county of Madison, and State of New York, have invented a new and improved Loading and Unloading-Device for Wagons; and I do hereby declare that the following is a full and exact description thereof, which will enable others skilled in the art to make and use the same, reference being had to the accompanying drawings, and to the letters of reference marked thereon.

This invention relates to a new and improved loading and unloading-device for wagons, and of that class in which the team, which is attached to the wagon and draws it with its load, is rendered subservient in performing the work of loading and unloading.

The object of this invention is to obtain a device, for the purpose specified, which will be extremely simple, and, in its application to a wagon, in nowise involve any material alteration in the construction of the latter, and hence be capable of being directly applied to any ordinary team, truck, or hay-wagon previously used without it.

The characteristic feature of my invention consists in a novel construction and arrangement of parts, whereby the driver, by a very simple manipulation, may transfer at once the draught-power or "pull" of the team from the wagon to the derrick-tackle and brake, the application of the latter to the wagon-wheels, simultaneously with the application of power to the derrick-tackle, being essential in order to prevent the wagon from moving during the operation of loading and unloading.

This invention also consists in a novel construction of detail parts, pertaining to the derrick and the tackle thereof, and also to the draught-pole, whereby the object of the invention is fully attained.

In the accompanying sheet of drawings—

Figure 1 is a vertical longitudinal section of my invention applied to a hay-wagon, the line of section passing through the centre.

Figure 2, an inverted plan of the front part of the same.

Figures 3 and 4, detached views of draught-poles pertaining to the same.

Similar letters of reference indicate like parts.

A represents a hay-wagon, the principal portion of which may be constructed in the usual manner, and therefore does not require a special description.

At the rear part of the body of the wagon there is a derrick, B, the upright or standard of which passes through a cross-piece, b', on the rear part of the top of the body, and has its lower end stepped in a cross-piece, b, secured to the bottom of the body directly underneath b', (see fig. 1.) The standard or upright is composed of two parts, a $\times$ a $\times$ x, the abutting ends of which are formed by an oblique cut, as shown by the dotted line in fig. 1. These two parts, a $\times$ a $\times$ x, are connected together by a strap-joint or hinge, C, the pintle of which is at the upper end of the oblique cut. The lower strap of the joint or hinge is constructed in the form of a socket, c, to receive, when the upper part, a $\times$ x, of the standard is an upright position, the lower portion of said part, and thereby render the standard as firm as possible.

D is the arm of the derrick, secured to the standard by a metal strap, b $\times$, attached to each side of D, and passing around the standard. The arm D is supported by a bar, d, the lower end of which is secured to the lower end of the upper part, a $\times$ x, of the standard, and some distance below the pintle of the joint or hinge C. This supporting-bar is inclined from a vertical line as little as possible, and this, in connection with the oblique abutting ends of the parts a $\times$ a $\times$ x of the derrick-standard, the sockets c to receive the lower end of a $\times$ x, and the attaching of the lower end of the supporting-bar d to a $\times$ x, below the pintle of the joint or hinge C, render the derrick stiff and firm. The connecting of the arm D to the upright or standard of the derrick by the metal strap b $\times$, forms a strong attachment without weakening the standard, as would be the case were the arm fitted to it by a mortise and tenon.

The constructing of the standard of the derrick in two parts, connected by a hinge or joint, is essential, as it admits of the upper part being folded over, to enable the derrick to pass through barn-doors, &c.

A high derrick for hay-wagons is a necessity, and hence the advantage of having them jointed, so as to turn or fold over.

A shorter derrick, B', may be used for loading and unloading other articles, such, for instance, as baled goods, coal, &c.

This derrick is not provided with a jointed or hinged standard, and is considerably shorter than derrick B. Its arm D' is attached to the standard by a metal strap, c^x, precisely like that of the arm D of derrick B. The arm D', however, is braced or supported differently from the arm D, a stout wire, d^x, being passed through D' near its outer end, and extended around the upper end of the standard. This forms a very simple, cheap, and efficient brace.

The short derrick may be fitted in the centre of the wagon, as shown in fig. 1, or at the rear end of the same, where the jointed derrick is placed.

A^x represents the brake-bar of the hind wheels of the wagon, and e^x the shoes at the ends of said bar. The brake-bar is supported from the rear of the wagon-body by pendants f^x, the upper ends of which are pivoted to the body; and to the centre of the brake-bar there is attached a pendant-bar, B^x, which is connected by a rod, M, to a lever, L, at the front part of the wagon, and having its fulcrum at N.

The front end of lever L has a rope, K, which extends upward, and is attached to the frame J at the front of the wagon-body.

The front brake-bar, B^x, is arranged in the usual way, and has a curved rod, C^{xx}, attached, which extends over the front axle, and has a pendant-lever, G, passing through it, said lever being connected to the bolster g^x, the connection forming the fulcrum of the lever, as shown clearly in fig. 1. A sheave, R', is secured to the lower end of the lever G, through which a rope, C^x, passes.

This rope is attached to the bottom of a sheave, R, at the rear end of a slide, S, of the draught-pole, and passes through sheave R', then through sheave R, around a pulley, h^x, in the rear brake-bar A^x, and thence extends upward over pulleys U U at the upper part of the derrick B, as shown clearly in fig. 1.

In case the shorter derrick, B', is to be used, the rope C^x may pass around a pulley, i^x, in the pendant-bar B^x, and thence up through an opening in the lower part of the standard of derrick B', and extends upward in a groove in the rest of the standard to the top of the derrick, where it passes over the pulleys U' U'.

P represents the permanent or fixed portion of the draught-pole, which is secured, as usual, by a bolt, p, between the hounds F F of the front axle.

The slide S of the draught-pole is placed under the fixed portion, P, and has a clip, j^x, secured to it near its rear end, a friction-roller, k^x, being in the upper part of the clip, to bear upon P and reduce friction. The front part of the slide S passes through a clip, l^x, provided with friction-rollers, k^x, at the front part of P, and the double-tree is attached to S at the point m^x.

In figs. 3 and 4 modifications of the draught-pole are shown. Either form may be used. They differ slightly in construction, but not in principle.

The slide S is connected to P by a bolt, Q, which passes through P into S, the bolt having a spiral spring, W, attached to it, which spring has a tendency to keep the bolt down in the slide S. The bolt Q is connected, by a rope, I, with rope K.

From the above description it will be seen that when the bolt Q is down in slide S, and S connected with P, the wagon will be drawn along as usual, and when it is desired to raise and place an article on the wagon, the driver stops the team until the derrick-rope is attached to the article, and then draws up the rope K, which raises the lever L and applies the rear brake to the hind wheels.

At the same time the rope K is raised the bolt Q is raised, in consequence of its rope I being attached to K, and, the team being started, draws the slide S outward, and the article is raised. The pull of the team on the derrick-rope C^x, in consequence of said rope passing through the sheave R' attached to lever G, causes the front brake to be applied, and the wagon will therefore be retained or prevented from moving while the derrick is in operation.

It will be seen, of course, that the sheaves R' R perform an important function. They admit of the articles being raised and lowered by the derrick a suitable distance, under a moderate length of movement of the team. The movement of the latter is restricted within certain limits, say six feet; and articles, such, for instance, as hay, would require to be raised eighteen feet when the wagon is nearly loaded. Hence the necessity of having the sheaves, and these may be single or double, as circumstances require.

The rod M may be connected to the rear brake-bar A at different points, as shown at n^x, in order to regulate the pressure as required.

Having thus described my invention, I claim as new, and desire to secure by Letters Patent—

1. The slide S of the draught-pole, applied to the permanent or fixed part P thereof, substantially as shown, in combination with the bolt Q connected with the cord K of the brake-lever L, all arranged to operate in the manner substantially as and for the purpose set forth.

2. The spring W applied to the bolt Q, when said bolt is used in connection with the slide S of the draught-pole, and connected with the brake-actuating mechanism, substantially as and for the purpose set forth.

3. The combination of the lever L, adjustable rod M, rope K, pendant-bar B^x, and rear brake-shoe A^x, as herein described, for the purpose specified.

4. The connecting of the front brake-bar B^x to the slide S of the draught-pole through the medium of the lever G and the tackle-rope C^x, arranged in the manner substantially as and for the purpose set forth.

5. The sheaves R R', in combination with the lever G, sliding pole S, rope C^x, front and rear brake-shoes

A^X B^X, and derrick, whereby the wagon is stopped and the load elevated at one operation, as herein shown and described.

6. Constructing the derrick B with a jointed standard, the two parts a^X a^{XX}, each of which have oblique abutting ends, connected by a strap-hinge or joint, provided with a socket, and having the arm D of said derrick connected to the standard by a metal strap, b^X, and supported or braced by a bar, d, the lower end of which is attached to the lower end of the upper part, a^{XX}, of the standard, substantially as shown and described.

F. M. REYNOLDS.
